UNITED STATES PATENT OFFICE.

L D MOUSER, OF IMPERIAL, NEBRASKA.

PIPE LIFTING OR LOWERING MACHINE.

SPECIFICATION forming part of Letters Patent No. 627,007, dated June 13, 1899.

Application filed August 3, 1898. Serial No. 687,665. (No model.)

To all whom it may concern:

Be it known that I, L D MOUSER, a citizen of the United States, residing at Imperial, in the county of Chase and State of Nebraska, 5 have invented new and useful Improvements in Pipe Lifting or Lowering Machines, of which the following is a specification.

My invention relates to improvements in pipe lifting and lowering machines, and pertains to a machine adapted to either lift or lower a pipe or rod through the medium of a lever, all of which will be fully described hereinafter and particularly referred to in the claims.

15 The object of my invention is to provide a simple and effective machine for raising and lowering pipes in Artesian and other wells, though it may be used for handling rods equally as well.

20 In the accompanying drawings, Figure 1 is a perspective view of a machine embodying my invention. Fig. 2 is a detached view of the lower dog. Fig. 3 is a longitudinal sectional view through the lower dog.

25 The invention is especially adapted for lifting a pump, detaching it from the stock, and then raising or lowering the tube or stock of the pump, as well as for handling rods and metal tubes in connection with Artesian wells.

30 Referring now to the drawings, A indicates the base-sills, which are united at their rear ends through the medium of a cross-piece B. Projecting from these sills A are the vertical standards B', and between the lower ends of 35 these vertical standards is a block D, a securing-bolt E passing through the sills, the lower ends of the standards, and the block D, thus uniting them all together. Resting upon the tops of the ends of these sills, projecting beyond the standards B', are the blocks F and

40 G. Formed in the upper faces of these blocks and intermediate their ends are sockets H, which are adapted to receive the pivotal points I of the lower dog J. This lower dog 45 consists of a bar K, which carries the said pivotal points I, and secured to this bar K and extending parallel to each other are the plates L, of which there are two at each side. Secured between these plates L, near their upper ends and adjacent the bar K, is a plate M, which is secured between the plates L. The

lower edge of this plate M, between the plates L, is recessed, as shown at N, and this recess is tapered at its under side to form a sharp upper edge.

55 Situated between the plates L at their outer ends is a second plate P, which has one side pivoted between the plates L and its other side held in position by means of the set-screw Q, which passes through the upper plate L, 60 through the plate P, and screws into the lower plate L. The plates L at one side are provided with a plurality of pivotal openings R, whereby the plate P may be adjusted back and forth to bring it nearer to or farther from 65 the plate or jaw M. These plates M and P, in fact, form jaws, the upper edge of the lower one, P, being curved, as shown at S, the edge of the curve being tapered at the top and also at its lower side, as illustrated. By means of 70 the adjustment of this plate the lower dog is adapted to be adjusted to pipes or rods of different sizes, as will be readily understood.

The block F upon the top of one of the sills A is pivoted at its rear end at the point T and 75 is held at its opposite end by means of a vertical pin U. The object in having this block to swing to one side is to enable the lower dog to be detached and used to clamp the head of the pump that is being removed for un- 80 screwing it from the stock.

The pivotal points I of the lower dog are held in their sockets against vertical movement through the medium of the bands a, which are curved upward at their centers to 85 pass over the said pivotal points I and bolted at their ends to the blocks F and G, respectively.

Journalized to the side of one of the sills A is a rock-shaft b, which is provided at its rear 90 end with a U-shaped crank c, forming a foot-piece, by means of which the rock-shaft may be oscillated, for a purpose to be specified hereinafter. The opposite and forward end of the rock-shaft is provided with a crank- 95 arm d, and attached to this crank-arm d is a hook e, adapted to catch in an eye f, carried by the outer end of the lower dog J.

Projecting upward from the blocks F and G are standards g, attached to the said blocks 100 in any desired manner and connected at their upper ends by cross-bar h. These bars are

connected with the standards B through the medium of the braces i. The cross-bar h is provided with a hook k, adapted to coöperate with the upper dog in a manner which will be hereinafter set forth.

The upper ends of the standards B' are united by means of a cross-head k'. Passing through the upper end of these standards B' is a lever pivotal pin l, upon which the lever 10 m is fulcrumed. The short end of this lever is provided with a hook n, the said hook having a straight portion p secured to the top of the said lever, and this straight portion p of the hook is provided with a projection q. 15 This projection is adapted to enter the spout of a pump for the purpose of lifting the pump up, as will be readily understood.

The upper dog consists of two levers 2, which are bulged outward, as shown at 3, for 20 the reception of the stock of the pump or a tube or rod, and their outer ends diverge, as shown at 4, and are connected through the medium of an adjustable bolt 5. This bolt has one end screw-threaded and adapted to 25 pass into the end 4 of one of the levers 2, and its opposite end is flat and passes between jaws 6 of the other lever and is held in position by means of a set-screw 7. Through the medium of this construction the removal of 30 the set-screw 7 will enable the bolt to be turned and the levers to thus be adjusted as may be desired. The opposite ends of these levers are provided with openings 8, into and through which the lower ends of the links 9 35 pass. The outer sides of these links 9 are provided with the offsets 10, and passing around these links is a ring 11. The ends of the ring 11 are preferably made square or straight to fit the corresponding edges of the 40 links 10, and the upper ends of these links are provided with openings 12, through which a ring 14 passes, said ring adapted to receive the hook n before mentioned. Passing through one of these levers 2 and abutting against the 45 other is a set-screw 16, by means of which the levers may be forced apart for the purpose of releasing a tube and by means of which the levers can also be prevented from closing so tightly upon a tube as to injure it. In operation 50 when the upper dog has been placed around the tube to be raised the ring 11 will fall sufficiently upon the links to hold them clamped against the tube, and yet by the lifting of the ring the levers 2 can be caused to 55 release the tube.

Braces 15 have their upper ends connected with the standards B' and their lower ends united with the sills A, the bolts which unite these braces to the sills passing through a nut 60 at the lower side and are pointed, as illustrated in dotted lines, for the purpose of entering the platform and preventing the lifting-machine from slipping.

In operation the projection p of the lever 65 m is placed in the spout of the pump (when a pump is to be raised) and the pump lifted.

The upper dog is then placed in position around the top of the pump and the stock also passed through the lower dog J. The downward pressure upon the long end of the 70 lever m will lift the stock, and when released the stock is caught and held by the lower dog J, all of which is well understood by those skilled in the art.

When it is desired to lower a tube in position, the bolt 5 is hooked over the hook k of the bar h, and by a downward pressure upon the lever m the upper dog will be slightly raised, which will release it to the degree it is lifted by the lever m, thus permitting the tube 80 to drop a short distance, and this dropping of the tube is also effected through the medium of the rock-shaft b and by the foot of the operator upon the U-shaped crank c, which will either lift or depress the lower dog 85 J, as will be readily understood. These parts last mentioned are only brought into operation when it is desired to lower a tube into position.

Having thus described my invention, what 90 I claim, and desire to secure by Letters Patent, is—

1. A pipe lifting and lowering device comprising an elongated base provided at one end with standards, a lifting-lever fulcrumed between said standards, a lifting-dog attached to the short end of said lever, a holding-dog pivotally supported in the base under the lifting-dog, and a rock-shaft journaled to one of the longitudinal beams of the base and extending its entire length and having at one end a transversely-rocking crank, connected to the free end of the holding-dog by a link and the other end provided with an operating-crank below the handle end of the lever, whereby the operator can operate both the crank and the lever by his foot and hand at the same time, substantially as described. 95

2. In a machine of the character described, a lifting-dog consisting of two levers one carrying a bolt, the free end of which is adjustably connected to the other lever, said levers being shaped to receive a pipe, links attached to the other ends of the levers and having shoulders a ring adjustably supported thereon and an eye connecting the free ends of the links and adapted to be attached to a lifting-lever, substantially as described. 110

3. In a machine of the character described, a base, provided with vertical standards, a lever fulcrumed thereon, a supporting-dog carried by the base, a bracket projecting above the base and provided with a hook, a lifting-dog carried by the said lever, one end of the lifting-dog adapted to engage the said hook, the parts constructed to operate substantially as described. 115

4. In a machine of the character described, a base, standards projecting therefrom, a lever fulcrumed upon the standards, a holding-dog carried by the base, a lifting-dog attached to the lever, said lifting-dog comprising two 120

levers pivotally and adjustably connected at one end, links connecting their opposite ends, the opposite ends of the links adapted to be connected with the said lever, a ring coacting with the links, the links provided with shoulders adapted to support the ring at different points, substantially as described.

5 In testimony whereof I have hereunto set

my hand in the presence of two subscribing witnesses.
